UNITED STATES PATENT OFFICE.

ROBERT L. BROWN AND GUS BROWN, OF MAYVIEW, MISSOURI.

INSULATOR.

1,035,415.

Specification of Letters Patent. Patented Aug. 13, 1912.

Application filed March 1, 1911. Serial No. 611,566.

To all whom it may concern:

Be it known that we, ROBERT L. BROWN and Gus Brown, citizens of the United States, residing at Mayview, in the county 5 of Lafayette, State of Missouri, have invented a new and useful Insulator, of which the following is a specification.

This invention relates to electric conductors, and more especially to insulators; and 10 the object of the same is to produce an insulator which will avoid the necessity for the tiewire now commonly employed. This object is accomplished by the construction hereinafter more fully described and 15 claimed, and as shown in the drawings wherein—

Figure 1 is a side elevation of this insulator, showing two conductor wires in section passing therethrough. Fig. 2 is a side 20 elevation of the insulator taken at right angles to the position from which Fig. 1 is seen. Fig. 3 is a central vertical section on the line 3—3 of Fig. 2 and Fig. 4 is a section on the line 4—4 of Fig. 1, both Figs. 25 3 and 4 showing at their right hand sides a slight modification.

In the drawings the numeral 5 designates the body of this insulator which is of glass, porcelain, or the like, and in the lower end 30 of this body is a cavity 6 such as is usually provided for engagement with the pegs on the cross trees of a pole or other support, the upper end of the body 7 being made conical or of other desired shape, and pos- 35 sibly fanciful to a slight degree, and the whole by preference made of one piece of insulating material. Its size is immaterial, but by preference we make it a little larger than usual because as will be seen below it is 40 intended to hold and insulate two conductor wires, and it is of course desirable that these wires shall stand so remote from each other between the supports that they will not come in contact under the influence of the 45 elements.

Through the body is formed what might be called two longitudinal openings 8, because they extend longitudinally of the line wires L, and as best seen in Fig. 1, these 50 openings are a little oval in shape, that is to say, they are taller than they are wide. By preference they are more than twice as tall as the diameter of the wire, and a little wider than the said diameter, so that the 55 wire when it passes through them is free laterally to rise as seen at the right side of

Fig. 3 or to fall into the lower end of the opening as elsewhere shown. These openings 8 extend straight through the body of the insulator between its upper and lower 60 ends and are parallel with each other, and each opens outward through the side of the body in a slot 9 communicating at its inner end with the opening at about the center of the height of the latter, as best seen in Fig. 65 2. Between its ends each slot opens downward through the bottom of the opening 8 in a beveled wall 10 which is continued downward and outward as shown in Fig. 3 and merges into the periphery of the body 70 5 about at the point 11. This wall 10 is rather narrow at its upper end so as to leave two lugs 12, and somewhat wider at its lower end as shown at 13 in Fig. 2 and where the lugs are undercut as at 14 in 75 Fig. 3.

The numeral 20 designates two spring tongues, such as strips of resilient metal, which are the only fastening means necessary with this insulator to hold the two line 80 wires L in place. Each tongue is of a width to pass between the inner faces of the lugs 12, and of such length that its upper end will stand beneath the overhanging lip 21 along the top of an opening 8 when its 85 lower portion is secured to the body 5 of the insulator. This lower end may be secured to the body of the insulator in a variety of ways, of which we have illustrated two. Perhaps the simplest is to mold or 90 embed the metallic tongue in the glass as shown at 22 at the left of Figs. 1 and 3, although obviously this would not permit the tongue to be withdrawn as for replacing it if it should become broken. At the 95 right of Figs. 3 and 4 we have shown the glass as provided with upright flanges 23 between which the lower end of the tongue is inserted as by pushing it downward from above, and this would obviously permit the 100 removal of the tongue when desired. The upper end of the tongue may be sprung under the lip 21 by forcibly flexing the exposed portion of the tongue.

The body of the tongue between its ends 105 lies across and normally stands somewhat remote from the beveled wall 10 and forms a retainer for the wire L as shown at the left of Fig. 3. When it is desired to remove the wire (or when the wire is being inserted) the 110 operator by bearing his thumb upon the tongue at the point 13 depresses it to the

dotted position shown at the right of Fig. 3 so as to push its upper extremity away from the lip 21 and thus clear the throat 24 of the opening 8 so that the wire (which of course has been raised as here shown) can be moved into or out of said throat at will.

Thus it will be seen that we have produced an insulator made almost entirely of one piece of glass, the only metal in its construction being the tongue which may be molded therein or which can be slipped behind the flanges 23 if the latter be provided.

It is obvious that instead of making the insulator double for two line wires L as shown, it could be made with the above described construction at one side only and would support but a single wire.

What is claimed is:

1. The herein described insulator comprising a body of insulating material having an opening across its side whose upright dimension is greater than the diameter of the wire, said opening having a throat leading out through the side of the body beneath an overhanging lip, and an inclined wall leading downward from the bottom of the opening between its ends, and lugs at opposite sides of the upper portion of said wall; combined with a spring tongue secured at its lower ends to the body of said insulator and extending thence upward over and remote from said wall and between said lugs, with its upper end passing across said throat and its upper extremity engaged behind the said lip.

2. The herein described insulator comprising a body of insulating material having an opening across its side whose upright dimension is greater than the diameter of the wire, said opening having a throat leading out through the side of the body beneath an overhanging lip and an inclined wall leading downward from the bottom of the opening between its ends; combined with a spring tongue secured at its lower ends to the body of said insulator and extending thence upward over and remote from said wall, with its upper end passing across said

throat and its upper extremity engaged behind the said lip.

3. The herein described insulator comprising a body of insulating material having an opening across its side whose upright dimension is greater than the diameter of the wire, said opening having a throat leading out through the side of the body beneath an overhanging lip; combined with a spring tongue secured at its lower end to the body of said insulator and extending thence upward, with its upper end passing across said throat, and its upper extremity engaged behind the said lip.

4. The herein described insulator, the same comprising a body of insulating material having an opening along its side with a throat leading out said side under an overhanging lip, the bottom of said opening having between its ends an inclined lower wall and the body below said wall having upright flanges projecting toward each other; and a spring tongue whose lower end is removably inserted between said flanges, whose body extends upward over and remote from said wall, and whose upper extremity is engaged behind said lip.

5. An insulator, provided with a lateral notch having a reduced inlet slot and an enlarged wire receiving portion, and a resilient closure for the enlarged receiving portion disposed at the juncture thereof with the reduced inlet slot.

6. An insulator, comprising a body of insulating material having an opening across its sides whose upright dimension is greater than the diameter of the line wire, said opening having a throat leading out through the side of the body, and an outwardly tensioned spring closure for said opening.

In testimony that we claim the foregoing as our own, we have hereto affixed our signatures in the presence of two witnesses.

ROBERT L. BROWN.
GUS BROWN.
